UNITED STATES PATENT OFFICE.

ALBERT KRAUTH, OF HAMILTON, OHIO.

AUTOGRAPHIC REGISTER.

No. 839,299.

Specification of Letters Patent.

Patented Dec. 25, 1906.

Application filed July 31, 1906. Serial No. 328,617.

To all whom it may concern:

Be it known that I, ALBERT KRAUTH, a citizen of the United States, residing at Hamilton, in the county of Butler and State of Ohio, have invented certain new and useful Improvements in Autographic Registers, of which the following is a specification.

My invention relates to an improvement in autographic registers.

10 One of the objects of my invention is to provide an autographic register with means whereby one of the record-strips is fed to a record-roll and in which such record-strip is caused to be moved at a slower rate of feed than the delivery-strips, producing what is known as a "summary record-strip."

Another object of my invention is to provide means whereby the record-roll can be readily and conveniently thrown out of commission and when in such position can be conveniently withdrawn from the machine or refed.

25 Another object of my invention is to provide means for frictionally revolving said record-strips, whereby an accurate feed of the record-roll is maintained irrespective of the number of coils of paper wound upon said record-roll.

30 The features of the invention are more fully set forth in the description of the accompanying drawings, forming a part of this specification, in which—

35 Figure 1 is a side elevation of my improved register. Fig. 2 is a central vertical section of the same. Fig. 3 is an enlarged sectional view of the actuating mechanism of the register, illustrating the record-roll in its released or idle position. Fig. 4 is a section on line *x x*, Fig. 2. Fig. 5 is a section on line *w w*, Fig. 2. Fig. 6 is a section on line *v v*, Fig. 2. Fig. 7 is an enlarged detailed sectional view of the record-roll, illustrating the means employed for securing the record-strip to said roll.

45 In registers of this class it has been found difficult to control what is known as the "record summary-strip," in order that such summary amounts may be uniformly spaced throughout the entire length of the record-strip. This has been difficult to regulate, owing to the varying diameters of the record-roll during usage.

With my construction a uniform feed of the record-roll irrespective of its diameter is obtained, and, further, the feed of this record-roll can be easily changed to suit varying

sizes of sales-strips without building or constructing special machines for every size of sale-strips.

1 represents the base of the machine.

60

2 represents the side frames secured to the base and forming the body of the register.

3 represents the frame supporting the actuating mechanism of the register pivotally connected to the side frames 2.

65

4 represents a roll of paper journaled in the frame 3, and 5 6 represent rolls of paper journaled in the side frames 2.

7 represents a writing-table.

8 represents the ordinary hinged cover 70 having a suitable opening over the writing-table.

The feeding of the paper is accomplished as follows: 9 represents a delivery-roll journaled in the frame 3, its axle projecting 75

through the frame 3 and upon one end of which is fixed the handle 10. 11 represents a gear fixed to revolve with the delivery-roll 9 and in mesh with a pinion 12, fixed to the delivery-roll 13.

Said delivery-roll 13 is held in tensional contact with the delivery-roll 9 and supported in position by the following mechanism: 14 15 represent arms pivotally supported upon the rod 16 and to the free

end of which the delivery-roll 13 is journaled. 80 17 represents a connecting-rod fixed to the opposite ends of the arms 14 15. 18 represents a tension-plate pivotally mounted upon rod 16 and under upward tension caused by

the spring 19 coiled around and the free ends 90 secured to the rod 16. The coils being on each side of the tension-plate, thus any downward movement of the tension-plate 18 will strain the coils, causing the same to apply an upward tension.

The free end of said plate 18 bearing against the rod 17 transmits the tension to said rod and delivery-roll, maintaining said delivery-roll in frictional

contact with the delivery-roll 9. The release of said frictional contact of the delivery-roll 13 with the delivery-roll 9 is accom-

plished as follows: 20 represents a rod pivotally mounted to the frame 3, and 21 represents cams fixed to the rod 20, adapted to

engage the arms 14 and 15, and when actuated by the handle 22 will bring the delivery-

roll 13 into or out of engagement with the delivery-roll 9, as desired. 23 represents a

ratchet-wheel fixed to revolve with the delivery-roll 9, and 24 represents a spring-con-

trolled pawl in engagement with the ratchet-wheel 23 for preventing reverse rotation of

105

110

the delivery-roll 9. 25 represents a roll journaled within the frame 3, and 26 represents a companion roll likewise journaled in the frame 3.

- 5 To effect a positive feed of the record-roll, the following transmission elements are provided: 27 represents a gear fixed to the stud-shaft at one end of the delivery-roll 9 and revolving therewith, and 28 represents a gear 10 in mesh with gear 27, fixed to the stud-shaft of the roll 25. These gears 27, 28 are preferably mounted outside of the frame 3 and are adapted to be readily removed and other change-gears applied to impart a different 15 ratio of feed to the rolls 25, 26, according to the length desired to feed the record-strip, which must be governed by the size of the sale-strip, for it being understood that for one size of sale-strip it may require one revolution of the handle to move the same sufficiently beyond the delivery-strips to be torn off, while a second size of sale-strip might require more than one complete revolution of the handle to free the same. A represents a 20 gear fixed to the stud-shaft of the roll 25 at the opposite end from that of gear 28. b represents an intermediate gear loosely journaled on the frame 3 and in mesh with gear a and a gear c, fixed to a stud-shaft of roll 26 25 for imparting a positive feed to roll 26. The intermediate gear b is employed to change the direction of rotation of roll 26 opposite to that of roll 25, thereby enabling the proper rotation to be imparted to the record-roll 30 which is in frictional contact with the rolls 25 and 26. Therefore it will be seen that it is necessary to change the feed of the summary record-roll to correspond with the particular size of sale-strip used in the machine; 35 otherwise the totals upon the record-strip would be spaced too irregular to be useful.
- The record-roll is operated and controlled as follows: 30 represents a rod rigidly secured to the frame 3, and upon said rod the record-roll frame 31 is pivotally mounted. This frame 31 is provided with the forwardly-projecting limbs 32 at each side thereof. 33 represents notches formed in the free ends of said limbs, into which the studs of the record-roll 34 are loosely journaled. 35 represents a plate fixed to the frame 31 at one end, the opposite end of said plate encircling the rod 30. 36 represents a spring the ends of which are secured to the rod 30 and the intermediate portion of the spring bearing against the plate 35, imparting upward tension to the record-roll frame 31 for maintaining frictional contact of roll 34 with rolls 25, 26. 37 represents a rod loosely journaled in the frame, provided with the cams 38, 39, fixed to move with said rod, and 40 represents a handle fixed to rod 37 for manipulating the same. The cams 38, 39 are adapted to bear against the frame 31, and as the lever 40 is 45 depressed it will swing the frame to a posi-

tion shown in Fig. 3, releasing the record-roll 34 from engagement with the rolls 25, 26, at the same time causing the record-roll to occupy a position for convenient removal. The record-roll 34 is provided with a groove 70 extending along the entire face thereof, into which the rod 41 is adapted to be fitted. (See Fig. 7.) Thus to thread the paper to the record-roll 34 the rod 41 is removed and the paper passed over the groove of the record-roll 34, when the rod is inserted, depressing the paper into the groove and holding the same securely in position for feeding.

The strips of paper are fed into the machine over the following course: The record-strip is fed from the record-roll 4 over guide-roll 42, thence over the table 7, guide-roll 43, and thence between delivery-roll 9 and frame 30 to the record-roll 34. The original and second strips are fed from their respective 85 rolls 5, 6 over the roll 44, table 7, and between the delivery-rolls 9, 13, thence out of the machine, where they can be torn off by contact with the roll-guard 45, of course it being understood that the usual carbon 90 strips are placed between the strips of paper for manifolding.

Having described my invention, I claim:

1. In a machine of the class described, a writing-table over which the strips are 95 passed, a pair of delivery-rolls at the front end of the table, a crank-handle for operating said delivery-rolls, a pair of rolls in driven connection with said delivery-rolls, a recording-roll, and means so supporting said recording-roll that it is adapted to be thrown into frictional engagement with said driven rolls, substantially as described.

2. In a machine of the class described, a writing-table, a pair of delivery-rolls, means 105 for actuating one of said rolls, a pair of rolls in driven connection with said delivery-rolls, a hinged member, the recording-roll journaled on said hinged member, means for attaching the record-strip to said recording-roll, and means for swinging said hinged member whereby it may be moved to position of frictional contact with said driven rolls or swing free therefrom, substantially as described.

3. In a machine of the class described, a writing-table, main delivery-roll mechanism, summary recording mechanism comprising a pair of rolls in driven connection with the delivery-rolls, a hinged member and a recording-roll journaled in said hinged member, means for throwing said hinged member so as to place said delivery-rolls in driving relationship with the said summary recording mechanism, substantially as described.

4. In an autographic register, a writing-table, a pair of delivery-rolls, a series of strips of paper adapted to be fed over the writing-table and between the delivery-rolls, a record-roll, one of said strips of paper being se- 130

cured to said record-roll, transmission-rolls in driven connection with said delivery-rolls, means for frictionally engaging said record-roll with said transmission-rolls for actuating said record-roll, and means for throwing said record-roll out of engagement with said transmission-rolls, substantially as described.

5. In an autographic register, a writing-table, a record-roll, a record strip of paper adapted to be fed over said writing-table upon said record-roll, transmission-rolls, delivery-rolls, transmission elements between said delivery-rolls and transmission-rolls for imparting a varying ratio of rotation to the transmission-rolls from that of the delivery-rolls, means for frictionally engaging said record-roll with said transmission-rolls for actuating said record-roll, and means for throwing said record-roll out of engagement with 15 said transmission-rolls, substantially as described.

6. In an autographic register, a writing-table, a pair of delivery-rolls held in tensional contact with each other, a series of strips of paper adapted to be fed over the writing-table and between the delivery-rolls, a record-roll detachably supported, one of said strips of paper secured to said record-roll passing over said writing-table, transmission-rolls 25 in positive transmission with said delivery-rolls, means for frictionally engaging said record-roll with said transmission-rolls for actuating said record-roll, and means for throwing said record-roll out of engagement with said transmission-rolls, substantially as described.

35 7. In an autographic register, a writing-table, a record-roll, a record strip of paper adapted to be fed over said table upon said record-roll, transmission-rolls, means for bringing said record-rolls into frictional con-

tact with said transmission-rolls for driving said record-roll, delivery-rolls, means for feeding said delivery-rolls, transmission means between said delivery-rolls and transmission-rolls for driving said transmission-rolls, one or more strips of paper adapted to be fed over the writing-table and between the delivery-rolls, means for throwing said record-roll out of engagement with said transmission-rolls, means for removing said record-roll, and means for securing said record strip of paper to said record-roll, substantially as described.

45 8. In an autographic register, a writing-table, a record-roll, a record strip of paper adapted to be fed over said table upon said record-roll, transmission-rolls, means for bringing said record-roll into frictional contact with said transmission-rolls for driving said record-roll, delivery-rolls, means for feeding said delivery-rolls held in tensional contact with each other, means for separating said delivery-rolls, said record-strip adapted to be fed between said delivery-rolls, transmission means between said delivery-rolls and transmission-rolls for driving said transmission-rolls, one or more strips of paper adapted to be fed over the writing-table and between the delivery-rolls, means for throwing said record-roll out of engagement with said transmission-rolls, means for removing said record-roll, and means for securing said record strip of paper to said record-roll, substantially as described.

50 75 In testimony whereof I have hereunto set my hand.

ALBERT KRAUTH.
